Specification for Design.

Patented July 21, 1914.

Application filed May 15, 1914. Serial No. 838,884. Term of patent 14 years.

To all whom it may concern:

Be it known that I, EMANUEL ZAHN, a citizen of Austria, and a subject of the Emperor of Austria-Hungary, residing at Blumenbach, Austria-Hungary, have invented a new, original, and ornamental Design for a Glass or Similar Article, of which the following is a specification, reference being had to the accompanying drawing, forming part hereof, wherein—

Figure 1 is an elevation of a glass illus-

trating my new design, and Fig. 2 is a plan view thereof.

I claim:

The ornamental design for a glass or similar article, as shown.

In testimony whereof I affix my signature in the presence of two witnesses.

EMANUEL ZAHN.
